LAUNDRY MANGLES

Arne Wilhelm Stenestam and Karl Tage Schill, Hjo, Sweden, assignors to Hjo Fabriks AB, Hjo, Sweden

Filed Dec. 3, 1963, Ser. No. 327,590

Claims priority, application Sweden, Dec. 4, 1962, 13,030/62; Aug. 27, 1963, 9,326/63

5 Claims. (Cl. 38—49)

This invention relates to improvements in laundry mangles. Laundry mangles with two or three rollers, one of which may be pressed by spring force into an operative position against one or two motor driven rollers and then be moved into an inoperative position by manually operated means, suffer from the drawback that considerable force is required to overcome the spring pressure against the adjustable roller when moving the latter into its inoperative position.

This invention has for its object the elimination of the above drawback, thus facilitating operation of the mangle.

The improved laundry mangle according to the present invention is mainly characterized in that it comprises means that are combined with the roller system of the mangle and adapted to be brought, through manual actuation of one of the means, into direct or indirect cooperation with the motor driven roller of the mangle, and with one of its driven rollers respectively, in order to effect a movement of the adjustable roller into inoperative position, and to stop the motor automatically at the same time. A spring combined with the said means and with the adjustable roller is adapted to restore said adjustable roller automatically to an operative position when the motor is started.

The invention will appear more clearly from the following detailed description when taken in conjunction with the accompanying drawings showing by way of example, the preferred embodiments of the inventive concept.

In the drawings:

FIGURE 1 shows diagrammatically an embodiment of the invention in combination with a laundry mangle with a roller system comprising two rollers that are mounted in stationary bearings and driven by an electric motor, and a roller which is adjustable relative to these rollers and can be pressed against them by spring force,

FIGURE 1a is similar to FIG. 1 but shows the device in its operative position.

FIGURE 2 is a diagrammatic view, on smaller scale of an inner end wall in the casing of the mangle, as well as the driving motor and power transmission means between the motor and the mangle roller system,

FIGURE 3 is a vertical section on smaller scale through the mangle,

FIGURE 4 is a perspective view of the same, and

FIGURE 5 shows a modification of the device illustrated in FIG. 1,

FIGURE 5a is the front view of the apparatus shown in FIGURE 1.

Referring now to the drawings, the numerals 1 and 2 designate rollers mounted in stationary bearings, and 3 is a roller that can be moved into contact with these rollers by spring force. A sprocket wheel 5 is rigidly fastened to the end portion of the shaft 4 of the lower roller 2. 6 is an electric motor and 7 is a belt pulley or V-belt pulley fastened to the shaft of the electric motor. 8 is a belt pulley or V-belt pulley to which the motor

2

power is transmitted by means of a belt or rope 9. Fastened to the shaft of the belt pulley 8 is a sprocket wheel 10 which transmits the motor power by means of a chain 11 to the wheel 5 and the roller 2. A sprocket wheel 12 is fastened to the shaft 16 of the roller 3, and a similar sprocket wheel 14 is fixed to the shaft 13 of the roller 1. The sprocket wheels 5 and 14 have the same number of teeth or cogs, and a driving chain 15 placed on these wheels transmits driving power from the motor driven roller 2 to the roller 1.

The ends of the shaft 16 of the roller 3 are mounted in bearings 17, which are displaceable in the lateral direction of the rollers 1 and 2. Shafts 4 and 13 of rollers 1 and 2 respectively, are mounted in bearing brackets 18, which are fastened to the mangle casing, for instance to inner end walls provided in the casing. The brackets 18 are provided with recesses 19 forming parallel, opposed edges on which bearings 17 are slidably supported. The bearings 17 are provided with grooves 20 which receive the edges of the recesses 19 in the brackets 18. The recess 19 of each bracket 18 forms a certain angle with an imaginary diametrical connecting line extending between rollers 1 and 2.

Rotatably mounted in the brackets 18 is a shaft 21 which extends parallel or approximately parallel to the rollers 1 and 2. The end portions of this shaft 21 protrude outside the brackets 18 and carry rigidly mounted arms 22 extending in one and the same direction. Each arm 22 is pivoted at 23 to a rod 24 at one end of a link or turnbuckle 25' which is connected at the other end with one of the bearings 17. Each of these links or turnbuckles, which are adjustable, consists of a rod 25 that is rigidly connected with one of the bearings 17 and a sleeve 26 provided with internal, oppositely directed threads into which the parts 24 and 25 are screwed. The threaded parts 24 and 25 can be locked in their sleeves 26 by means of nuts 27 which are screwed thereon.

An arm 28 is rigidly connected with one end portion of the shaft 21. At a distance from one end of this arm 28, another arm 29, which is actuated by a spring 35, is journaled on a pivot 30 carried by arm 28. The arm 29, which is preferably made of spring steel, has a notch 31 located adjacent its free end. A circular or approximately circular disk 32 is fastened to the end portion of the shaft 4 of the motor driven roller 2. This disk 32 is provided with an eccentric pin 33 located at a distance from the disk centre. The free end portion of the arm 28 carries a plate 34 that serves as a holding means for a spring device 36. 37 is a microswitch and 38 is a pendulum-like arm, whose upper end rests against a ball catch 39.

The numeral 40 designates an acuator member which is displaceable in a sleeve and has its inwardly directed end portion adapted to engage and actuate the arm 38 when the member is pushed inwardly. The outwardly pointing end portion 41 of the member 40 is shaped to be conveniently pressed by the operator's finger. One end 43 of a helicoidal spring 42 is hinged to the arm 28, and the other end 44 of this spring is hinged to the mangle frame or to a support 45 fastened to the frame.

A brake disk 46 is fastened to the end portion of the shaft 16 of roller 3 that protrudes outside the bracket 18. The brake disk 46 is adapted to press against a brake block 47 fastened to a plate 48, when the roller 3 is moved into an inoperative position.

The arm 28 carries a plate 49 that serves as a holding means for a ball detent 52, which is supported slidably

in a sleeve 50 with a spring 51 tending to force the detent outwardly of the sleeve. When the roller 3 assumes the inoperative position the ball detent enters a recess 53 which is provided in the disk 32 and has a shape substantially corresponding to that of the ball detent.

During mangling the adjustable roller 3 is pressed against the rollers 1 and 2 by the spring 42 connected with the arm 28 (FIG. 1a). When roller 3 is to be set into an inoperative position, the end portion 41 of actuator member 40 is pressed inwardly, thereby actuating the arm 38, which in turn swings the arm 29 toward the disk 32 fastened to the shaft 4 of the roller 2. When the disk 32 is turned, the pin 33 will engage with the notch 31 in the arm 29 and cause this to exert an upwardly directed pull on the arm 28 connected with the shaft 21, thus turning this shaft by a certain angle of rotation. This movement of the shaft 21 is imparted to the arms 22 fastened to the shaft and to the links or turnbuckles 25' and effects an outward displacement of the bearings 17 in the recesses 19, and thus the roller 3 is moved into an inoperative position and out of engagement with the rollers 1 and 2. When spring 36 actuates the microswitch 37, the current to the motor is interrupted. For restoration of the roller 3 to an operative position the end portion 41 of actuator member 40 is again pressed, the pin 54 of the arm 38 moving the spring device away from the microswitch 37 so that the circuit is closed and the mangle starts. When the arm 29 disengages from pin 33 due to the further rotation of disk 32 the arm is moved by action of the spring 35 into an inoperative position and comes to rest against a part 55 provided on the arm 38. The inoperative position of arm 38 is indicated by broken lines in FIG. 1.

FIG. 5 shows a modification of the device illustrated in FIG. 1, similar parts in FIGURE 5 being indicated by a prime designation. Here, the figure 66 designates an arm, the outwardly directed portion of which can have the form of a handle 67. The arm 66 is adjustable in vertical direction and adapted to actuate the arm 38 with which it is connected. The swingable arm 28' carries at one end a lug 68 provided with a set screw 69 or the like. When roller 3' should be placed in the inoperative position, the arm 66 is swung downwardly, its movement actuating the arm 38', which in turn swings the arm 29' toward the disk 32' mounted on the shaft 4' of roller 2'. In operative position, i.e., during mangling, the arm moves out of contact with a microswitch 70. This position is indicated by full lines in FIG. 5. The said actuation of the arm 66 interrupts two phases of the current to the electric motor, since the pin 54' loses contact with the microswitch. Through the engagement between arm 29' and the pin 33' on disk 32' the set screw 69 is moved into contact with a microswitch 71, which interrupts the current to the motor. To restore the roller 3' to an operative position the arm 66 is moved upwardly, the pin 54' of arm 38' now actuating the microswitch 70 so that current is fed to the motor. When arm 29' is disengaged from pin 33', the arm is set by action of the spring 35' to inoperative position and thus comes to rest 60 against the arm 55'.

The adjustable roller is in known manner provided with a mangle cloth which can be wound onto and off the roller. In front of the mangle rollers is a board 57 which can be swung up and down by means of two stays 58. A slide plate 60 (FIG. 3) directed obliquely downwardly and forwardly is fastened to the mangle casing 59 below the rollers 1, 2 and 3 and forms, together with shields 61 and 62, a space for collection of mangled articles. The shield 61 can be swung inwardly at the same time as the board 57, and the shield 62 can be swung downwardly and inwardly.

A protecting grate, generally designated by 63, is placed in front of the adjustable roller 3. The upper part is 75

stationary, whereas the lower part 65 is pivoted at 72 and swingable into various positions, and is adapted to actuate a switch (not shown) which cuts out the current to the motor 6 when the grate is swung outwardly or by a certain angle inwardly from the vertical direction.

The lower grate part 65 is furthermore adapted to reverse the rotation of the rollers when in the swung-up position.

The lower grate part 65 thus positively protects the machine operator from injury, since even an unintentional actuation of the part results in interruption of the current.

The invention is not confined to the embodiments described above and illustrated in the drawings, as many modifications are possible without abandonment of the invention spirit.

We claim:

1. A laundry mangle comprising:
at least one driving roller;
a driven roller;
means supporting said driven roller parallel to said driving roller;
a shaft;
means supporting said shaft for rotation about an axis parallel to the axis of said driving roller;
a lever firmly connected at one end to one end of said shaft and extending radially outwardly of said shaft and adjacent said driving roller;
link means connecting said driven roller with said lever;
resilient means connected with said lever and tending to swing said lever in a direction away from said driving roller whereby said driven roller is moved into engagement with said driving roller;
an arm pivoted on the other end of said lever, said arm having a hooked end;
a disc;
a shaft supporting said disc adjacent said driving roller and for rotation concentric with the axis of said driving roller;
a pin carried eccentrically on said disc; and
means for swinging said arm into the path of movement of said disc when said disc is rotated, whereby said pin engages the hooked end of said arm and said lever is swung in a direction towards said driving roller thereby disengaging said driven roller from said driving roller.

2. A laundry mangle in accordance with claim 1 wherein said means for swinging said arm in the path of movement of said disc comprises:

a push-button actuator; and
a pendulum-like arm located alongside said actuator and adjacent said first-mentioned arm, said actuator being adapted to engage and swing said pendulum-like arm whereby said pendulum-like arm engages and swings the first-mentioned arm.

3. A laundry mangle in accordance with claim 1 wherein:

said link means comprises a turnbuckle connected at one end to said lever;
another lever firmly connected to said shaft at the other end and extending radially outwardly of said shaft and adjacent said driving roller;
another turnbuckle connected at one end with said other lever;
bearings carried on the ends of said driven roller and connected with the other ends of said turnbuckles; and
bearing brackets located at each end of said driven roller, said bearing brackets having slots for slidably supporting said bearings;
4. A laundry mangle in accordance with claim 1 further comprising:
a brake disc connected with said driven roller; and

a brake block engaged by said brake disc when said driven roller is moved to an inoperative position.

5. A laundry mangle in accordance with claim 1 further comprising:

a motor for rotating said driving roller;

5

a lug carried at the other end of said lever;

a set screw carried by said lug; and

a microswitch engaged by said set screw when said lever

is swung for disengaging said driven roller from said

driving roller, said microswitch being actuated by

10

said set screw to de-energize said motor.
